UNITED STATES PATENT OFFICE

2,589,139

TIMER-SWITCH CONTROL MECHANISM

Chauncey Gordon Reynard and Charles D. Hoover, Fort Wayne, Ind., assignors to Basic Products Corporation, Fort Wayne, Ind., a corporation of Indiana

Application December 27, 1948, Serial No. 67,534

1 Claim. (Cl. 161—1)

1
This invention relates to timer-switch control mechanism and more particularly to timer-switch mechanism adapted for the defrosting of refrigerators and similar uses.

An object of the invention is to provide switch control mechanism of improved construction effective for periodically breaking a circuit leading to a refrigerator for defrosting the refrigerator. A further object is to provide switch mechanism and means for adjusting the position of the switch mechanism to vary the period of time in which said switch is open. Yet another object is to provide novel means for driving a timer device while also providing for the ready adjustment of the timer device through manual movement thereof. A still further object is to provide an actuating arm driven by timing mechanism in combination with a movably mounted switch and with means for accurately adjusting the switch support whereby the actuating arm engages the switch for a greater or lesser period during its rotation by said timing mechanism. Other specific objects and advantages will appear as the specification proceeds.

The invention is shown in an illustrative embodiment by the accompanying drawing, in which—

Figure 1 is a vertical sectional view of apparatus embodying my invention; Fig. 2, a vertical sectional view, the section being taken as indicated at line 2—2 of Fig. 1; and Fig. 3, a transverse sectional view, the section being taken as indicated at line 3—3 of Fig. 1.

In the illustration given, 10 designates a casing formed of plastic, metal or any other suitable material. Supported within the casing is a synchronous motor, the housing of which is indicated by the numeral 11. The synchronous motor drives a shaft 12. Since the synchronous motor and the shaft 12 driven thereby are of well-known construction, a further detailed description is believed unnecessary. It will also be understood that clockwork or any other timing mechanism may be employed for rotating the drive shaft 12. The casing is equipped with rearwardly extending prongs 13 adapted to be received within the socket of an electric outlet and the prongs 12 are connected by means of the strap 14 and arms 15 for wiring connections (not shown) with the electric apparatus in the casing.

As shown more clearly in Fig. 3, the casing 10 is provided with a rear plate 16 and with an integral forwardly extending frame member 17. A front plate 18 is secured to the standard 17 and extends across the front of the casing 11.

2
Fixed to the plate 18 is a post 19 on which is mounted a sleeve member 20. Fixed upon the sleeve is a timer disk 21 having peripheral teeth 22. A pin 23 extends inwardly from the disk 21 and is equipped with a roller 24. The roller 24 is adapted to engage a switch, as will be later described, for the opening of the switch. The sleeve 20 is equipped at its outer end with an outer sleeve or insulator 25 and a handle or knob 26 is secured to the outer sleeve by a setscrew 27. The knob 26 may be provided with an indicator arm 28. Preferably, the surface 29 may be equipped with an indicator scale, etc., for use with the indicator 28.

15 The fixed post 19 is equipped at its outer side with a head 30 and a compression spring 31 is housed between the head 30 and the bottom of the recess 32, as shown best in Fig. 3. The spring normally urges the sleeve 20 inwardly, as shown in Fig. 3. However, the knob 26 may be drawn outwardly against the force of spring 31 to disengage the teeth 22 of the disk 21 from the drive shaft 12 so that the disk 21 may then be freely rotated to bring it into any desired position.

20 The shaft 12 is provided with spaced drive pins 33 and 34 as shown best in Fig. 1. The spaced pins engage the teeth 22 of disk 21 and cause the disk 21 to be rotated as shaft 12 is rotated.

25 We prefer to employ a movably mounted switch together with means for adjusting the switch in an arcuate path or in a path toward or away from the actuating roller 24. In the specific illustration given, we provide a support or beam 35 having at one end a depending arm 36 pivotally mounted upon a stud 37. At its other end, the beam 35 is provided with a depending arm 38 having an elongated slot 39 therein. A stud 40 is fixed upon the mounting plate 18 and carries a forwardly extending post 41. Upon the post 41 is mounted a sleeve 42 equipped at its inner end with a cam 43 eccentrically positioned upon the post 41. Fixed to the cam sleeve 42 is a cam insulator or sleeve 44 and a cam knob 45 is fixed to the sleeve 44 by a setscrew 46. The knob 45 may also be provided with a pointer 47 for use with a scale or other indicator device. By rotating the knob 45, the cam sleeve 42 is turned so as to move the cam 43 within the slot 39 of arm 38, thus raising or lowering the switch support or beam 35.

30 Suspended from the beam 35 is a switch 48. Any suitable form of switch may be employed. In the illustration given, a well-known form of switch is illustrated. A bracket arm 49 is sus-

pended from the beam 35 and is apertured to receive the spring members 50 and 51. The spring member 50 is provided with an opening receiving the depending spring member 51 and it carries at its inner end a contact 52. A fixed contact 53 is supported upon the beam 35. The spring member 51 has a depending arm portion 54 adapted to engage the roller 24. As the spring 54 is pressed upwardly, the upper spring member 51 is flexed downwardly at its inner end so as to separate the contacts 52 and 53, as shown in Fig. 1. However, as the roller 24 moves out of contact with the lower arm 54, the spring members 50 and 51 assume their normal position in which the inner contact 52 is pressed upwardly against contact 53. Since such switch structure is very well known and no claim per se is made thereto herein, a further detailed description is believed unnecessary. It will be understood that suitable wiring connections lead from the switch to the refrigerator so that upon the opening of the switch 48, current to the refrigerator or other electric device ceases to flow.

Operation

In the operation of the structure, the synchronous motor steadily rotates the shaft 12 and the spaced pins 33 and 34 rotate the timer disk 21. When the timer disk 21 brings the pin 23 and its roller 24 to the position shown in Fig. 1, the roller raises the lower arm 54 of switch 48 to break the contacts 52 and 53 and thus current to the refrigerator fails to flow. The roller 24 holds the switch arm 54 in elevated position for a period of time, as, for example, one hour or two hours, etc., to effect defrosting of the refrigerator. After the lapse of the desired length of time, the roller 24 clears the arm 54 and the spring switch automatically brings contacts 52 and 53 together, thus restoring the current flow to the refrigerator.

When it is desired to manually adjust the timer disk 21, this may be accomplished by drawing the knob 26 outwardly against the force of spring 31 to disconnect the teeth 22 of disk 21 from the drive pins 33 and 34 of shaft 12 and the disk 21 may then be freely rotated to the desired position and upon release, the spring 31 again brings the teeth 22 of disk 21 into alignment with the drive pins 33 and 34 of shaft 12. Thus, if it is desired to have the refrigerator current shut off at about twelve o'clock or one o'clock at night, the disk 21 may be set in the above manner so as to bring about such result. In the setting operation, the pointer 28 is moved to a point on the scale showing the time at which defrosting will begin.

Refrigerators of different makes and individual refrigerators of the same make vary substantially in operation so that a period of defrosting which

is satisfactory for one refrigerator is not satisfactory for another. Further, as a refrigerator changes in efficiency of operation after several years of service, it is often desired to change the defrosting period. By mounting the switch beam 35 upon a pivot stud and by swinging the beam upwardly or downwardly through the rotation of cam 43, the switch arm 54 is raised or lowered relative to the actuating roller 24. Thus, the period in which the actuating roller 24 is in contact with the switch arm 54 is decreased or increased depending upon the position of beam support 35. By movement of the cam 43, the period of defrosting may thus be varied from an hour or less to several hours and this result is achieved by merely rotating the cam knob 45.

While in the foregoing specification, we have set forth much of the structure in considerable detail for the purpose of illustrating one embodiment of the invention, it will be understood that such details of structure may be varied widely by those skilled in the art without departing from the spirit of our invention.

We claim:

25 Timer mechanism comprising a clock motor provided with a step-down gear box and an output shaft adapted to rotate continuously at a speed of one revolution per hour, a pair of spaced drive pins mounted on said shaft, extending parallel to the axis thereof and symmetrically disposed with respect thereto, a toothed gear having forty-eight teeth, said gear being mounted near said drive pins for periodic engagement therewith and intermittent rotation thereby, the average rotational speed of said gear being one revolution per day, a follower mounted for revolution in synchronism with said gear, switch mechanism intermittently actuated by said follower during rotation of said gear, and means for retracting 30 manually the toothed gear in an axial direction to disengage the same from said drive pins to permit manual adjustment of the relative positions of said follower and said pins.
